United States Patent Office

Des. 184,558
Patented Mar. 10, 1959

184,558

COLLAPSIBLE TUBELIKE CONTAINER

Frank E. Brown, Glendale, Calif., assignor to Unette Corporation, Livingston, N. J., a corporation of Delaware

Application May 2, 1958, Serial No. 50,726

Term of patent 14 years

(Cl. D58—17)

Fig. 1

I claim:

The ornamental design for a collapsible tubelike container, as shown.
